UNITED STATES PATENT OFFICE.

THOMAS ALEXANDER BOYD AND HAROLD ARTHUR BOYD, OF GLASGOW, SCOTLAND.

YARN-TENSIONING DEVICE.

1,333,059.

Specification of Letters Patent.

Patented Mar. 9, 1920.

Application filed January 19, 1920. Serial No. 352,560.

To all whom it may concern:

Be it known that we, THOMAS ALEXANDER BOYD and HAROLD ARTHUR BOYD, subjects of the King of the United Kingdom of Great Britain and Ireland, and residing at Shettleston, Glasgow, Scotland, have invented a certain new and useful Improvement in Yarn-Tensioning Devices, of which the following is a specification.

10 This invention relates to a yarn tensioning device associated with a pendulous member supporting a bobbin, cheese or the like which is rotated by the pull of the yarn as it is unwound.

15 A construction according to the invention includes a pendulous member mounted to swing on an axis above, and in the same vertical plane as the axis of the bobbin, cheese or the like, the latter or a brake wheel 20 on which it rests and which participates in the rotation of the bobbin, cheese or the like being unwound, being adapted to contact with and receive drag from a fixed brake, the pendulous member being so balanced 25 that the pull of the yarn pulls the bobbin, cheese or the like away from the fixed brake when an undue strain comes on the yarn.

30 The invention is illustrated by way of example in the accompanying drawings in which Figures 1 and 2 are elevations at right angles to each other.

Referring to the drawings, 1 denotes a bobbin mounted on a brake wheel 2 coaxial with a vertical spindle 3 carried in an oil 35 socket 4, the tubular hub of the bobbin being impaled on the spindle 3.

The socket 4 is of T-shape and to each end of the horizontal limb of the T-member is attached a wire 5 extending upward for a 40 suitable distance and out-turned at its upper end as at 6 to form a pivot. The wires 5 are braced together to form a pendulous carrier swinging on the coaxial pivots 6 which enter bearing orifices in a bracket 7 vertically 45 above the socket, the pivotal axis of the pendulous carrier being in the same vertical plane as the spindle 3.

Contiguous with the brake wheel 2, at the side of the bobbin opposite that from which 50 the yarn is drawn, is a fixed brake shoe 8 of leather or other material.

By means of an adjustable weight 9 the pendulous member is urged in the direction to press the brake wheel 2 against the fixed 55 brake 8 to the required extent.

As will be understood, should the yarn be

subjected to strain in excess of that predetermined by the adjustment of the weight, the bobbin and brake wheel will be momentarily withdrawn from the fixed brake and 60 thus relieved from drag.

In the instance selected for illustration there is employed a live spindle 3, it being understood however that it is not essential that the spindle be rotatable: further, the 65 brake shoe may be arranged to coöperate directly with the periphery of the lower bobbin flange.

What we claim is:—

1. For controlling the unwinding of yarn 70 from a bobbin, cheese or the like, in combination, a vertical spindle to receive the bobbin, cheese or the like, and permitting rotation of the bobbin, cheese or the like in the unwinding of the yarn, a pendulous support 75 for said spindle, said support pivoted on an axis located above and in substantially the same vertical plane as said spindle, and a brake for imposing drag on the yarn, said pendulous support being so mounted and 80 balanced as normally to maintain the bobbin, cheese or the like under the influence of said brake, but adapted to withdraw the bobbin, cheese or the like from said brake when the yarn is exposed to excessive strain. 85

2. For controlling the unwinding of yarn from a bobbin, cheese or the like, in combination, a vertical spindle adapted to receive the bobbin, cheese or the like, a brake wheel applied to said spindle, a pendulous support 90 for said spindle and brake wheel, said support pivoted on an axis located above, and in substantially the same vertical plane as said spindle, a fixed brake contiguous to the periphery of said brake wheel, said support 95 so balanced that said brake wheel is normally hinged against said fixed brake, said support being free to move on its pivot to retract said brake wheel from said fixed brake when the yarn is subjected to undue strain. 100

3. For controlling the unwinding of yarn from a bobbin, cheese or the like, in combination, a vertical spindle adapted to receive the bobbin, cheese or the like, a brake wheel on said spindle, on which brake wheel the 105 bobbin rests, a socket to receive said spindle, a pendulous support for said socket, said support pivoted on an axis above said spindle and in substantially the same vertical plane as said spindle, a fixed brake contiguous to the periphery of said brake wheel, said support so balanced that said brake 110

wheel is normally urged against said fixed brake, said support being free to move on its pivot to retract said brake wheel from said fixed brake when the yarn is subjected to undue strain.

4. For controlling the unwinding of yarn from a bobbin, cheese or the like, in combination, a brake wheel rotatable around a vertical axis on the unwinding of the yarn, a brake shoe coöperating with said brake wheel for imposing drag on the yarn, and a pendulous support for said brake wheel, said support mounted on a pivot above

and in substantially the same vertical plane as the axis of said brake wheel, and being adapted to permit movement of said brake wheel away from said brake shoe when the yarn is subjected to undue strain.

In testimony whereof we have signed our names to this specification in the presence of two subscribing witnesses.

THOMAS ALEXANDER BOYD.
HAROLD ARTHUR BOYD.
